Primary Examiner — Cynthia M Chin*(74) Attorney, Agent, or Firm* — Ostrolenk Faber LLP(57) **CLAIM**

The ornamental design for a water scooter, as shown and described.

DESCRIPTION

FIG. 1 is a front, right side, perspective view of a water scooter showing my new design;

FIG. 2 is a rear, left side, perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate environmental material that forms no part of the claimed design.
